UNITED STATES PATENT OFFICE.

NELSON J. TUBBS AND WINSLOW ALLDERDICE, OF BALTIMORE, MARYLAND.

PUMP.

SPECIFICATION forming part of Letters Patent No. 249,273, dated November 8, 1881.

Application filed August 22, 1881. (No model.)

To all whom it may concern:

Be it known that we, NELSON J. TUBBS and WINSLOW ALLDERDICE, both of Baltimore city, State of Maryland, have invented certain new and useful Improvements in Pumps; and we hereby declare the same to be fully, clearly, and exactly described as follows, reference being had to the accompanying drawings, in which—

10 Figure 1 is a central sectional view of the pump, and Fig. 2 is a similar view of a modified form of valve.

Our invention relates to double-acting sucking and lifting pumps designed to produce a continuous flow of water, and especially adapted for use in narrow or bored wells. The features fitting the device for this purpose do not, however, impair its efficiency or adaptability for general use upon the surface as a water-forcing device.

The invention will first be described, and then pointed out in the claims.

In the drawings, A A' are the barrels, placed in juxtaposition, and provided with pistons and piston-rods a. The rods pass through stuffing-boxes B, having glands b of the usual construction, and are combined with a rock-shaft or other equivalent and well-known means for imparting to the pistons an alternating reciprocating motion in the barrels. The base-piece l has a nozzle, L, adapted for the attachment thereto of the inlet-pipe, should one be used, and opens at l' l' into the barrels A A'. Flap-valves M normally close the openings l'.

35 The cap-piece C' is connected with the base l by tie-bolts at the sides, and between the cap and the upper ends of the barrels is interposed a plate, K, having openings c' leading 40 from the barrels to the chamber D. From the latter the opening c leads to the stand or delivery pipe C. The latter is provided with an air-chamber in order to insure a uniform flow of water, or else the opening c is made some 45 distance below the top of the chamber D, attaining the same end. Within the chamber D are two disk-valves d, which are mounted upon the piston-rods a and seat over the openings c', as shown.

50 The pistons consist of two perforated disks,

I J, having a leather or rubber cup, j, interposed. They are slipped upon the lower ends, e, of the rods a until they abut against the shoulders, and are clamped in place by nuts E on the threaded ends f. The sections a' of the 55 piston-rods are smaller in diameter than the parts a, and upon them are mounted the valves F, as shown. In operation, as the pistons rise in the barrels a partial vacuum is formed therein and the water rises, lifting the valves M. 60 On the descent of the pistons the valves D and M fall and the valves F rise, allowing the water to pass the pistons, when, on the next upstroke, it is forced through the openings c c' 65 into the delivery-pipe C. The valves d close instantly upon the descent of the piston-rods, preventing the water carried up into the chamber D by the ascending piston from following the descending one.

The construction and arrangement of the 70 piston-valves F are such as to secure important results in point of immunity from danger of the pump getting out of order and cheapness and simplicity. The valves themselves are simple disks, and the parts of the piston perforated plates, just as they come from the sand, except that the lower face of the valve and the upper face of the plate J are trued.

In working the pump submerged or in hot water we dispense with the flap-valves M and 80 use a simple disk, as shown in Fig. 2, its play being limited by pins or studs n. For submerged use we also dispense with the cups j and substitute the ordinary water-packing.

The pump is compact and simple and not 85 liable to get out of repair—points of the greatest importance in pumps which are to be used in narrow or bored wells, or in other places requiring the pump to be raised to the surface to repair it in case any part wears out.

90 Either barrel works independently of the other, adapting the device for use in connection with a windmill. If the wind is light, one of the rods a is uncoupled from the rock-shaft and the other rod works alone.

Having thus described our invention, what we claim as new, and desire to secure by Letters Patent, is—

95 1. In combination with the cylinders placed in juxtaposition, and having induction and 100

education valves, as set forth, the piston-rods *a*, having reduced portions *a'* *e*, disk-valves *F*, perforated piston-disks *I J*, interposed perforated packing *j*, and nuts *E*, substantially as described.

2. In combination with the cylinders, placed in juxtaposition as described, the casing *c'* and chamber *l*, clamping the cylinders together, the valves *M*, perforated pistons *I J*, and

valves *D* and *F*, the latter being mounted upon reduced portions of the piston-rods, as set forth.

NELSON J. TUBBS.
WINSLOW ALDERDICE.
